(57) **CLAIM**

The ornamental design for a clip, as shown and described.

DESCRIPTION

FIG. 1 is a perspective view of a clip showing the design of the present invention;

FIG. 2 is another perspective view of the clip of FIG. 1;
FIG. 3 is a left side elevational view of the clip of FIG. 1;
FIG. 4 is a right side elevational view of the clip of FIG. 1;
FIG. 5 is a top view of the clip of FIG. 1;
FIG. 6 is a bottom view of the clip of FIG. 1;
FIG. 7 is a front elevational view of the clip of FIG. 1; and,
FIG. 8 is a rear elevational view of the clip of FIG. 1.
